UNITED STATES PATENT OFFICE.

WARREN BARNHART, OF CHICAGO, ILLINOIS.

DESIGN FOR TYPE.

SPECIFICATION forming part of Design No. 18,175, dated March 13, 1888.

Application filed January 11, 1888. Serial No. 260,456. Term of patent 14 years.

To all whom it may concern:

Be it known that I, WARREN BARNHART, a citizen of the United States, residing in the city of Chicago, county of Cook, and State of Illinois, have invented and produced a new and original Design for a Font of Printing-Type, of which the following is a specification, reference being had to the accompanying typographic impressions, which are exact representations of said design.

The character of this design is a moderately heavy solid-faced somewhat condensed type, without ornamentation, comprising capitals, small letters, characters, and points. Its chief peculiarity is the ending of the upper ends of the stem-lines of the M, V, W, and Y in the capitals and of the v and w in the small letters. This ending is a loop or hook turned to the left in the V and W, the hook on the right-hand stem being larger than that on the left hand. Minor peculiarities are the formation of the small g, in which the circle is above the base-line and the lower part is simply a waved line ending in a sharp point; also the ending of the small c and capital C in a downward stroke ending in a point and not turning upward, as in an ordinary font; also the finishing-strokes of the small letters h, k, m, n, and s, which extend below the line and are a long taper 30 ending in a dot; also, the main stems of the

capitals F, H, M, N, P, R, and Y extend below the line and turned to the left slightly and end in a sharp point; also, the capital J has a long stem and the hook consists in a short wave-line below the base-line; also, one stem of the 35 capitals H, I, N, and U terminates at its upper end in a flame-like line inclined to the right.

I claim--

The design for a font of printing-type herein 40 described and shown, having medium heavy solid-faced somewhat condensed letters, without ornamentation, and comprising capitals, small letters, characters, and points, and having letters, as M, V, W, and Y and the w and 45 v, whose stems terminate at their upper ends in hooks turned to the left, said hook being in the right-hand stem of the capital V and W larger than that of the left stem, and in the v and w both larger and above the line; also having letters, as H, I, N, and U, having one stem terminating at its upper end in a flame-like wave-line inclined to the right; also having small letters, as h, k, m, n, and s, whose finishing-stroke extends below the line and is a 50 55 long taper ending in a dot.

WARREN BARNHART.
